(No Model.)

R. W. FENWICK,
HAND GLASS TUBE CUTTER.

No. 513,965.

Patented Jan. 30, 1894.

UNITED STATES PATENT OFFICE.

ROBERT W. FENWICK, OF WASHINGTON, DISTRICT OF COLUMBIA, ASSIGNOR
TO ALEXANDER E. HUNT, OF SCRANTON, PENNSYLVANIA.

HAND GLASS-TUBE CUTTER.

SPECIFICATION forming part of Letters Patent No. 513,965, dated January 30, 1894.

Application filed March 20, 1891. Renewed July 7, 1893. Serial No. 479,806. (No model.)

To all whom it may concern:

Be it known that I, ROBERT W. FENWICK, a citizen of the United States, residing at Washington city, in the District of Columbia, have invented certain new and useful Improvements in Hand Glass-Tube Cutters; and I do hereby declare the following to be a full, clear, and exact description of the invention, such as will enable others skilled in the art to

10 which it appertains to make and use the same.

My invention relates to a hand glass cutter, and consists in such a cutter comprising two arms which are connected by one or more vertical pins, on one of which pins an arm of the implement vibrates or oscillates; one of said arms being provided with an exteriorly clamping piece, and the other with an interiorly acting incision-cutter; and also with novel means, such as hereinafter described, 15 for vibrating or oscillating one or both of the arms, so as to cause the clamp to bear against the outer surface of tubing being incised, and the incision-cutter to bear against the inside of the same, and thus insure the cutting of 20 incisions, or determined lines of fracture in 25 incisions, or determined lines of fracture in the tubing, so that glass tube-sections of determined lengths adapted for gages and other uses, can be readily removed from the glass tubing in which the incisions are made, by 30 gently tapping the tubing near the incisions, or determined lines of fracture.

It also consists in the combination of a toggle-lever mechanism, or its equivalent, for vibrating or oscillating one or both of the 35 clamping arms on one or both of the pins, and moving the forward end of the respective arms toward one another, and their respective rear lever-extension ends away from each other, thereby clamping the glass tubing on 40 the outside, and by pressure insuring a cutting contact of the incision cutter against the inside of the glass tubing, and the cutting of incisions or determined lines of fracture in such tubing.

45 In the accompanying drawings, Figure 1 is a partial side elevation and broken section of a hand implement for cutting incisions in glass tubing, illustrating my invention. Fig. 2 is a similar view of another form of the implement, according to my invention. Fig. 3 is a broken top view of Fig. 2. Figs. 4, 5 and

6 are broken side elevations and partial sections of other forms of the implement according to my invention, and Fig. 7 is a side view (partly in perspective) and a partial section, 55 of parts of the two arms of the implement, and the gage, as applied in relation to a piece of glass tubing on which incisions or determined lines of fracture are to be cut on its inner surface.

60 A, in the drawings, Fig. 1, designates the incision-cutter-carrying arm, and B the clamp piece, and gage-carrying arm of the hand glass cutting implement. These arms are connected at their rear, lever-extension ends by vertical pins as c, c'; and around one of these pins a spiral spring d may be wound. One end of the respective pins may be fastened securely in the arm B by a screw thread, or otherwise, while the other ends are passed up quite 65 loosely through passages e, e' in the arm A, said passages being of sufficiently greater diameter than the pins to permit the arm A to vibrate or oscillate, up and down, on the pins when pressure is applied in a manner to bring 70 the forward ends of the arms toward one another, and move their rear ends apart. For preventing the upper arm getting off of pin c, or rising thereon, a cotter or pin f is passed through the pin c just above the arm A. To 75 the arm B a link C of a toggle lever device D, is pivoted at g; and to the arm A an elbow lever E is pivoted at g', the shorter arm of said lever, and the angular bend thereof, being passed down through a slot h in the arm A, and 80 connected by a pivot g² to the upper end of the link C as shown. The long arm of the lever E extends forward above and over the arm A, and, by depressing it with the hand while 85 clasping and manipulating the implement, it 90 is caused to straighten the toggle device D, and thereby vibrate or oscillate the arm A upon the pin c, and force its forward end downward toward the forward end of the arm B, and its rear end upward away from the 95 rear end of said arm B. The spring d is compressed as the toggle device D is straightened, and as soon as the force upon the lever E is relaxed this spring throws up the forward end of the arm A and causes the toggle 100 device to assume its normal angular position shown in Fig. 1. On the front end of the arm

As a revolving incision-cutter F, or a diamond point, is applied in the usual manner, so as to enter the glass tube along with the arm; and upon the arm B a concaved or segmental 5 clamping piece G is constructed, or applied, so as to fit and bear forcibly upon the outside of the glass tube. The arm B has a scale marked upon it; and is also provided with a tubular stop gage H which is fitted to slide 10 upon the arm; it being confined by a set screw i and made adjustable so as to answer for gaging different lengths of sections to be cut from the glass tubing.

In Figs. 2 and 3, one of the two pins c, c' is 15 provided with a spiral spring d, and a cotter f; and the toggle device D is operated by two knobs E', E' applied upon horizontal extensions or spindle ends of the pivot g². The extensions of the pivot g² are passed through 20 slotted, sector shaped guide pieces g³ fastened, as illustrated in Fig. 3, to the sides of the arm A. By moving forward the pivot g² (with the knobs) in the sector-slots, the toggle device D' will be straightened, and the arm A 25 caused to operate in the same manner as when moved by the toggle device D in Fig. 1.

In Fig. 4, the arms A and B are connected by a single vertical pin c, which is provided with a spiral spring d, and kept in place by a cotter 30 or pin f; and for vibrating or oscillating the arm A on the pin c, a sliding wedge block E², which is applied between the rear lever-extension ends a and b of the arms, is provided. This block has one or more handle knobs as 35 E³, by which it is moved forward and back either by hand or a lever mechanism D², Fig. 6; and it is fitted in guiding channels p formed in the inner surfaces of the said extensions; and, by its form, it presses the rear, lever-extension end of the arm A, away from the extension end of the arm B when it is slid toward the pin c thereby causing the forward end of said arm A to approach arm B; and, when moved backward, allows the spring d to readjust said 40 arm to its normal position substantially as shown in Fig. 4. In Fig. 5 the arms A and B are connected in the same manner as in Fig. 4, and an inclined projection q is formed on each of the arms forward of the pin c, and 45 the arms are yoked by means of a sliding yoke I, having its inner bearing surface tapered to fit the inclined projections q. By sliding this yoke backward on the said inclines, either by hand, or a lever mechanism 50 D², Fig. 6, the forward end of the arm A will be forced toward the forward end of the arm B, and the clamping piece G made to bear against the glass tubing K while the cutter bears against the inside of the same.

55 In Fig. 6 the arms A and B are connected by pins as c and c', one of said pins (that c') being fastened at one end to the arm B while the other (c) is left loose at both of its ends; and on the pins spiral springs d, d' are applied. On each of the rear lever extensions a, b of the arms A and B, an inclined projection as q' is formed, and the arms are yoked

together by a yoke I', having its inner bearing surface tapered to fit the inclined projections q'. To this yoke, links C' are pivoted as at g⁵, and these links are pivoted as at g⁶ to elbow levers E⁴ which are pivoted as at g⁷ to the ends of the pin c; thus forming a toggle device D². By depressing the levers, in clasping the implement with the hand, the 70 links draw the yoke forward up the inclined projections, and thereby the arm A is caused to vibrate or oscillate, and its forward end to move toward the forward end of the arm B, thus causing the clamp piece G to press on the glass tubing K, and keep the cutter in effective operative contact with the said glass tubing K, which is to have incisions cut upon it. On relaxing the pressure of the hand upon the levers, the springs will readjust the arms to their normal positions.

In constructing the arms A and B, they will, as is commonly the case in some other hand implements of this type, be bent and shaped so as to have the incision cutter and clamping piece bear as nearly as practicable at a right angle to the axis of the tubing. It might be practicable, without departing from my invention, to have the clamping arm and its clamping piece shaped to enter the tubing, 90 and to bear upon the inside thereof; and the cutter to bear outside of the tubing, but I prefer the arrangement shown.

This implement is especially designed as an improvement on that type of hand glass cutter which has two arms connected by a horizontal pivot, one of said arms carrying the cutter and entering the glass tubing and the other carrying the clamping piece and bearing on the outside of said tubing. In operating the implement, the glass tubing is held in the left hand, and the implement in the right; and when the cutter and clamp are bearing against the tubing, said tubing is revolved several times, and by this means the cutter is caused to cut the desired incision at about a right angle to the axis of the tubing; and this done, the implement is removed, and by a slight tap on the tube near the incision, a section of tube for a gage can be separated 115 from the tubing; and thereupon the operation is repeated.

I do not claim anything shown and claimed, or might be properly claimed in the application of J. Odell Fowler, Jr., filed February 5, 1891, Serial No. 380,388, as my invention relates to that type of glass cutter wherein the cutter carrying arm and the clamping piece-carrying arm vibrate or oscillate and auxiliary means for oscillating an arm of the implement, in contradistinction to a glass cutter the arms of which make a straight reciprocating movement on vertical guides. Neither do I claim broadly a glass tube cutter comprising a bar with a cutter at one end, said bar being attached at or near the other end to another bar carrying a suitable bearing opposite the cutter of the first bar, the bars being so connected as to permit movement 125 130 135

toward and from each other and having an auxiliary connecting device connected to or bearing upon each bar, and with a projecting lever handle whereby the bars may be pressed 5 toward each other during the cutting. As I only claim, as hereinafter stated, specific means, constructions and combinations, therefore

What I claim as my invention is—

- 10 1. A glass tube cutter comprising two approximately parallel arms or bars, one carrying at its front end a cutter and the other at its front end a bearing opposite the cutter, a stud applied to the rear portion of one arm or bar and passing loosely through an opening in the other arm or bar, of a size sufficient to allow the bar to oscillate, a guide which in connection with the stud serves for keeping the two arms in the same plane, a
- 15 2. pin or stop on the stud, and a spring to hold the loose arm or bar out against the pin or stop, against which, as a fulcrum, the loose
- 20

arm or bar may be made to oscillate by the described means, whereby as the rear ends of the arms or bars are forced apart, the front 25 ends are pressed together during the cutting.

2. A glass tube cutter, comprising two approximately parallel arms or bars, one carrying at its front end a cutter, and the other at its front end an opposite bearing; two studs 30 connected to the rear portion of one arm or bar and passing loosely through appropriate sized openings in the other arm or bar which is arranged to oscillate, and a toggle lever device for oscillating an arm of the implement, 35 whereby as the rear ends of the arms or bars are forced apart the front ends are pressed together during the cutting.

In testimony whereof I hereunto affix my signature in presence of two witnesses.

ROBERT W. FENWICK.
